UNITED STATES PATENT OFFICE.

JOSEPH BREWER, OF NEW YORK, N. Y.

PHOTOGRAPHIC ROLL-FILM.

1,160,037.

Specification of Letters Patent.

Patented Nov. 9, 1915.

Application filed February 4, 1915. Serial No. 6,038.

To all whom it may concern:

Be it known that I, JOSEPH BREWER, a citizen of the United States, and a resident of the city of New York, borough of Manhattan, in the county and State of New York, have invented a new and Improved Photographic Roll-Film, of which the following is a full, clear, and exact description.

The invention relates to photography, and its object is to provide a new and improved photographic roll film arranged to permit the removal of any one or a number of exposed sections of the film for separately developing such removed section or sections in case the removed sections require more or less time for development than the remaining roll film sections.

In order to accomplish the desired result, use is made of a roll film having single exposure film sections, the sections being separably connected with each other to allow removal of any one of the sections after the exposures have been made for independent developing of the removed section relative to the remaining film roll sections.

A practical embodiment of the invention is represented in the accompanying drawings forming a part of this specification, in which similar characters of reference indicate corresponding parts in all the views.

Figure 1 is a face view of the roll film, its protective ribbon and its carrying spool; Fig. 2 is a like view of a single detached section of the roll film; Fig. 3 is a similar view of a pair of detached roll film sections fastened together for simultaneous development and independent of the remaining roll film sections; Fig. 4 is a longitudinal section of the roll film on the line 4—4 of Fig. 1; Fig. 5 is a similar view of the connected film sections on the line 5—5 of Fig. 3; Fig. 6 is a face view of the outer end of the opaque protective ribbon; Fig. 7 is a perspective view of one of the fastening devices for fastening the film sections together and Fig. 8 is a face view of a preferred form of the roll film.

The roll film A is wound on a spool B together with the usual opaque protective ribbon C, and the roll film A is formed of a series of sensitized exposure sections A' which may be in one continuous strip, as shown in Fig. 8, with the sensitized film sections separated by a transverse row of perforations A² to permit of separating any one film section A' from the adjacent ones after the ex-

posures have been made to allow of developing the removed section independently of the remaining film sections. The sensitized film sections may, however, be spaced apart and connected with each other at adjacent ends by connecting strips D of paper or other flexible material, as shown in Figs. 1, 2, 3, 4 and 5. Each of the connecting strips D is provided with a transverse row of perforations D' to allow of separating any one of the said film sections from the adjacent one, the same as above described in reference to the roll film shown in Fig. 8.

The first film section A' of each roll film A is connected at its starting end by a strip E with the ribbon C (see Figs. 1 and 4) to permit of properly winding up the roll film on the winding-up roll in the camera. The outer terminal C' of the ribbon C extends beyond the attaching strip E to allow of connecting the ribbon with the winding up spool prior to unrolling the film A in the camera for making the first exposure on the first film section.

Each connecting strip D is glued, pasted or cemented to the adjacent ends of successive sensitized film sections A', and the strip as well as the adhesive material used must be water and acid-proof to withstand the treatment while undergoing developing, washing and fixing. In practice, each row of perforations D' is adjacent the end of the next following film section A' and divides the strip into two parts D², D³, so that when the adjacent film sections are separated along the row of perforations D' then the portion D² of the connecting strip D on the preceding section is of a sufficient length to provide a convenient means for holding the film section without danger of touching the sensitized layer. Each connecting strip D is further provided on opposite sides of the row of perforations D' with pairs of apertures F and F', of which the apertures F' also pass through the corresponding film section to permit of fastening the remaining roll film sections together after one or two of the other sections have been removed. For this purpose use is made of fastening devices G, such as shown in Fig. 7, adapted to engage the pairs of apertures F, F' when moved in register with each other, that is, when superimposing the long end of a connecting strip D' of one section A' with the short portion of a connecting strip D of another film section A'. In a like manner if

two, three or more film sections A' have been removed from the roll film then such detached sections can be readily connected with each other by the use of the clips G, as shown in Fig. 3, to permit of developing the removed film sections simultaneously. The fastening devices G must be of a chemical-proof metal or coated with an acid-resisting enamel, so that the developing liquid or fixing bath is not affected by the metal.

The film shown in Fig. 8 is provided with pairs of apertures F³ on opposite sides of the transverse row of perforations A² to permit of fastening the remaining sections 15 of a film together by the use of fastening devices G after one or more such film sections have been removed for the purpose previously mentioned.

The film sections, as shown in Fig. 8, 20 have their sensitized portions terminating a distance from the perforations A² and the apertures F³ to provide non-sensitized holding portions A³ at each end of a film section A' for convenient manipulation thereof 25 without touching the sensitized portions in case a section is removed from the roll film and developed independently as above described.

The attaching strip E is provided with a 30 transverse row of perforations E' to allow of detaching the end of the roll film from the ribbon C after the exposures have been made and it is desired to develop the film.

It is understood that the film is used in 35 the camera in the usual manner and the film sections are provided with the usual identification marks, preferably consecutive numerals, to permit of identifying each section, and also to show such character in the 40 usual observation window when winding up the film to display the unexposed film section to the lens of the camera. After the exposures have been made and the film has been removed from the camera and taken to 45 the dark room any one film section A' can be detached from the remaining one and developed separately. The remaining film sections are again connected with each other by the use of the fastening devices G to 50 allow of developing the same as a unit. As previously stated, several film sections may be removed and fastened together for simultaneous developing, as indicated in Figs. 3 and 5.

Having thus described my invention, I claim as new and desire to secure by Letters Patent:

1. A roll film having single exposure sec-

tions separably connected with each other by transverse rows of apertures formed in the 60 roll film to allow removal of any one of the sections after the exposures have been made for independent development of the removed section, the said roll film having apertures on opposite sides of a row of perforations, and fastening means adapted to engage the apertures of the separated ends of the remaining roll film sections to allow of developing the remaining film roll sections as a single unit. 70

2. A roll film, comprising a continuous strip having sensitized exposure sections and having transverse rows of perforations separating the sections from each other to permit of removing any one or several of the 75 sections for separate development from the remaining sections, and means for fastening together the separated ends of the film roll to allow of developing the remaining film roll sections as a single unit. 80

3. A roll film, comprising a continuous strip having sensitized exposure sections and having transverse rows of perforations separating the sections from each other to permit of removing any one or several of the 85 sections, the strip being provided on opposite sides of each row of perforations with sets of apertures, and a fastening device adapted to engage the apertures of the separated ends of the film roll to allow of developing 90 the remaining film roll sections as a single unit. 90

4. A roll film having single exposure sensitized film sections and non-sensitized holding portions adjacent the ends of each sensitized film section; the said non-sensitized holding portions having rows of perforations separably connecting adjacent non-sensitized holding portions. 95

5. A roll film having single exposure sensitized film sections and non-sensitized holding portions adjacent the ends of each sensitized film section, the said non-sensitized holding portions having rows of perforations separably connecting adjacent non-sensitized holding portions, the latter also having pairs of apertures on opposite sides of each row of perforations. 105

In testimony whereof I have signed my name to this specification in the presence of 110 two subscribing witnesses.

JOSEPH BREWER.
